UNITED STATES PATENT OFFICE.

WILLIAM BELL EICHHOLTZ, OF NEW ORLEANS, LOUISIANA.

COMBINATION PLACKET-CLOSER AND SKIRT-SUPPORTER.

No. 845,538.

Specification of Letters Patent.

Patented Feb. 26, 1907.

Application filed May 28, 1906. Serial No. 319,172.

To all whom it may concern:

Be it known that I, WILLIAM BELL EICHHOLTZ, a citizen of the United States, residing at New Orleans, in the parish of Orleans and State of Louisiana, have invented a new and useful Improvement in a Combination Placket-Closer and Skirt-Supporter, of which the following is a specification.

This invention relates to a combination placket-closer and skirt-supporter, the object of the invention being to improve upon the present devices by supplying a double fastening means, as will appear hereinafter.

The invention consists of the novel features of construction hereinafter fully described, pointed out in the claims, and shown in the accompanying drawings, in which—

Figure 1 is a detail perspective view showing the various parts of the device assembled in position, the parts being detached from each other. Fig. 2 is a perspective view of the fastening member carried by the waistband. Fig. 3 is a plan view of the said member. Fig. 4 is a detail perspective view of an inner end portion of the skirt-band, showing the fastening member connected thereto. Fig. 5 is a similar perspective view showing the outer face of the skirt-band, the fastening member being shown partly in full lines and partly in dotted lines. Fig. 6 is a detail perspective view of the opposite end portion of the skirt-band, showing the fastening member coöperating with the member showing in Figs. 4 and 5. Fig. 7 is a plan view of the fastening member shown in Fig. 6. Fig. 8 is a face view of the last-mentioned member.

In these drawings, A represents a piece of straight wire, which adjacent each end is bent downwardly and upwardly to form depending hook members A', and the free end portions of the wire are bent to form eyes A''. The eyes A'' and the straight member A are stitched to the waistband, as shown in Figs. 1 and 2. The fastening member B is secured to one end of the skirt-band adjacent the placket-opening, and the member B consists of one piece of wire comprising a straight member B', arranged longitudinally upon the skirt-band and adjacent its upper edge and bent at each end to form essentially U-shaped members B'', which project above the upper edge of the band. The outer side members B''' of each of the U-shaped members B'' are bent in the same direction and parallel to the straight member B', as shown

at B⁴, and at the free end of each member B⁴ the wire of which the device is composed is bent to form loops B⁵ and B⁶, respectively, and the wire is then carried back from each of said loops, as shown at B⁷, parallel to the member B⁴, and the free ends of the said wire are bent to form eyes B⁸. The entire member is secured to the skirt-band by 60 stitches, as shown at Fig. 4. 65

It will be obvious from Figs. 4 and 5 that the loop B⁵ projects beyond the end of the skirt-band, and the members B⁴ and B⁷, adjacent the loop B⁶, are passed through the band from the inner to the outer side, so that the 70 loop B⁶ rests upon the outer side of the band, while the remainder of the device, with the exception of the projecting portions B² and a part of the loop B⁵, rests upon the inner side of the band. Upon the opposite end portion 75 of the skirt-band I arrange a fastening member to coöperate with the member B, and this member comprises a straight longitudinally-arranged wire member C, which is bent adjacent its ends to form oppositely-arranged 80 loops C', while the end portions are bent back to form hooks C'', each of said hook members extending in the same direction and in the same horizontal plane. In use the bow portions B² are engaged with the hook members 85 A', and the hook members C'', carried by the member C, are then brought over into engagement, respectively, with the loops B⁵ and B⁶. It will be obvious, therefore, that a 90 skirt is supported by the U-shaped members B², which engages the hook member A', secured upon the waistband, and the skirt is also doubly secured by the locking of the hook members C'' in the loops B⁵ and B⁶.

Having thus fully described my invention, 95 what I claim as new, and desire to secure by Letters Patent, is—

1. A device of the kind described comprising hooks carried by a waistband, a fastening device comprising a wire member secured adjacent one end of a skirt-band and provided with upwardly-extending U-shaped members projecting above the upper edge of the skirt-band to engage the hooks of the waistband, loops carried by the said fastening member, and alining hook members carried by the other end of the skirt-band adapted to simultaneously engage the loops. 100 105

2. A device of the kind described comprising a fastening member attached to the inner face of a skirt-band and having U-shaped portions extending above said skirt-band and 110

having longitudinally-arranged members each of which carries a loop, one of said loops projecting beyond the end of the band the other loop resting upon the outer face of said band, the members carrying the said loop passing through the band, the fastening member carried upon the opposite end portion of the said skirt-band and having hook members adapted to engage respectively, the 10 said loops, and hook members carried by a waistband in position to be engaged by the U-shaped portions of the first-mentioned fastening member.

3. In a device of the kind described a fastening member comprising a wire secured longitudinally upon the inner face of a skirt-band, U-shaped portions formed at the ends 15 of said wire, and projecting above the edge

of the band, a longitudinally-arranged wire member carried by the outer side members of each of said U-shaped members, one of said last-mentioned members extending through the waistband, a loop carried by the latter member and arranged upon the side of the band opposite the U-shaped members, and the other of the last-mentioned longitudinally-arranged members carrying a loop projecting beyond the end of the band, and means carried respectively by a waistband and the other end portion of the skirt-band 25 for engaging respectively the U-shaped members and the loops.

WILLIAM BELL EICHHOLTZ.
